UNITED STATES PATENT OFFICE.

GEORGE J. LAEMMLE, OF NEW ROCHELLE, NEW YORK, ASSIGNOR TO BARNET LEATHER COMPANY, INC., OF NEW YORK, N. Y., A CORPORATION OF DELAWARE.

METHOD OF SHEARING FUR PELTS.

No Drawing.

Application filed August 8, 1927. Serial No. 211,610.

This invention relates in general to a process for cutting the hair on fur pelts and more particularly has reference to a method of shearing calf skins.

5 Shearing and plucking form a very large factor in the dressing and finishing of pelts intended for the fur trade, depending upon the kind of skin being treated. It is desirable to cut away the over-growth to bring 10 to the surface the thicker and silkier hair underneath and also to reduce the thickness of the skin to any desired extent by cutting the hair to attain the desired weight. The amount of shearing and plucking varies with 15 each particular skin treated.

Pelts used for fur garments are limited to the thickness of the skin, and calf in general is the heaviest ever used. The character and color of the hair are the other determining influences. In size a calf skin is considered a large type, the other pelts running down to very small sizes such as squirrels, ermines and rats, all of which will give an idea of the variety, size and thickness of 20 skins that shearing machines must be able to work.

Excepting the unborn calves known as slinks, which form a very small percentage of the available skins, calf skins, if dressed 30 and left in their natural state, would be too heavy for garments and the hair would be too cowy to meet the requirements of the fur trade. It is therefore necessary that calf skins must be sheared so that the hair will 35 not be longer than from four to eight millimeters in length and such a process on calf skins must be very finely regulated so that a difference of one-half millimeter can be obtained.

40 Heretofore, however, it has been impossible to take advantage of these types of skins in imitating other furs or in even employing them in a natural state as the peculiarity in growth of the hair has prevented 45 an efficient shearing of the pelage. On most fur bearing animals, the hair runs from the neck to the tail in one direction except in minor portions of the underparts where a difference in direction so far as shearing is 50 concerned is unimportant as these parts of the skins are seldom used, and the shearing of the whole pelt may be easily carried on in a single operation.

The hair on a calf, on the other hand, 55 radiates out in all directions from a center

bald spot on the back, running toward the neck and tail from this center as well as the sides in a complete sun-ray design. In shearing an ordinary pelt having the usual growth of hair falling in a single direction 60 the pelage may be completely and evenly sheared against the fall of the hair in one operation.

Where it has been attempted to shear a calf skin, however, the hair has been cut 65 against the fall through the center bald spot after which the remainder is necessarily cut over the fall. In cutting over the fall of the hair only a portion is unevenly sheared and chatter marks or knife cuts invariably 70 produced, which render the skin impractical for further use. In attempting to overcome these difficulties calf skins have been sheared completely by running the skin through a machine in opposite directions in line with 75 the direction from the head to the tail of the animal. This method has produced an even poorer product, however, as in attempting to shear a skin in this manner portions of the hair are cut parallel to the line of 80 fall which makes the skin exceedingly liable to buckling, and causes chatter marks even more pronounced, besides making cuts in the skin which totally ruin the pelt.

An object of this invention is to provide 85 a method of completely shearing a calf skin.

Another object of this invention is to provide a method for evenly shearing calf skins without producing chatter marks or damaging 90 the skins.

A further object of this invention is to provide a method for shearing the hair on calf skins to any desired length without the appearance of the hair having been cut.

With these and other objects in view 95 which may be incident to my improvements, the invention consists in the method to be hereinafter set forth and claimed, with the understanding that the several necessary steps comprising my invention may be varied 100 in order or degree, without departing from the spirit and scope of the appended claims.

According to this invention I have developed a method whereby calf skins may be completely sheared without producing chatter marks or damaging the skin. In carrying out my invention, I first place the calf skin in any conventional shearing machine and cut one fall of the hair through the center bald spot in a line with the direction from 110

the head to the tail of the animal. Although it is not necessary to begin the operation at this specific point, as will be better understood after referring to the following description, I preferably continue the shearing over the fall of the hair after the center bald spot has been reached although this step may be dispensed with if so desired. I find, however, that in so doing, the disadvantages of regulating the feeding of the skin to a precise point on the pelt is avoided, and that the cutting that is effected over the fall of the hair removes certain quantity of the pelage that facilitates the subsequent operations to be hereinafter more fully set forth.

After the first shearing operation, I again consecutively repeat the operation progressively around the sides of the skin until the pelt has been fully sheared. I have found that six shearing operations carried on at angles of 45° with respect to the line through the bald spot on which each preceding operation was carried on, are generally sufficient to insure a completely sheared pelt, although, it is, of course, to be understood that I do not limit myself to any specific number of shearings, as additional operations may be found desirable in certain instances. I do not believe, however, that a calf skin can be efficiently sheared with fewer than six.

There is thus insured a cutting against the fall of the hair on every portion of the skin, thus insuring an evenly cut and uniform surface. It is manifest that the hair may be cut to any desired length to conform with the length of the hair of the particular fur which is sought to be imitated or of any conventional length that is deemed most suitable if it is intended that the calf skin is to be used in its natural state. As the hair is cut in six directions any natural waves or curls are evenly sheared as well as the straight hair, thus preserving the flowery or moiré character which increases the value of the pelt.

The preferred machine which I utilize for my process is that disclosed in the application of Prima E. Fontana Serial No. 211, 521 filed August 8, 1927 in the United States Patent Office. I find that it is necessary to support the screen in such a manner that the hair is directly presented to the cutting blades over a roller or similar surface so that the hair is made to stick out and be directly presented for only a small portion of its area to the cutting edge. In the usual types of machines known on the market the cutting is done along a narrow strip and, because of the size of a calf skin, the unsupported portions of the skin cause it to wrinkle so that it is extremely difficult to cut in the manner described in this application for patent without causing cuts on the skin proper as distinguished from the pelage. A calf skin must, to be marketable, have an extremely

short pelage as previously described and any cuts in the skin itself show in the finished product. A difficulty is encountered with calf skins that is not present in ordinary skins, since ordinary skins do not have to have the hair cut as short as is the case with calf skins since they are ordinarily not as heavy. In ordinary skins, therefore, where the skin proper is cut no material damage is done to the pelt for the cuts may be sewn up without the stitching appearing through the hair, whereas in the calf skins any repair by stitching the cuts is immediately apparent and renders the skin practically useless for fur purposes.

Up to the present time, therefore, the only machine which I find practical is that above referred to though I do not wish to be specifically limited to this application for the use of my process in such a machine as it may be possible that other types of machines will be devised which will enable me to carry out the process herein set forth without damage to pelts.

I have found that any other method of trying to cut with the fall of the hair and against the fall of the hair has had to be discarded because of the tendency of wrinkles forming as the skin is fed which cuts holes in the pelt, and it must be borne in mind that such holes cannot be repaired in sheared skins to avoid the seams showing in the finished garments.

It is obvious that this invention is in no wise limited to calf skin, but is applicable as well to any other types of fur pelts in which the hair grows in different directions similar to a calf skin, or to pelts where the general direction of the hair is unchanged or not radial but assumes a particular flowery character, such as caracul or moiré, in isolated portions of the skin where the hair suddenly becomes wavy and runs in varied directions for short intervals. It is particularly desirable that the shearing in such portions be done with absolute uniformity as the value of fur pelts increases with this particular moiré feature.

There is accomplished by this invention a method of shearing calf skins or any other pelts having a pelage composed of hair growing in radial directions from a common center, whereby all the hair may be evenly sheared by cutting all portions of the pelt against the fall of the pelage and in such manner that the chatter marks or damaging cuts in the skin are avoided and the hair cut to any desired length.

While I have described the preferred embodiment of my invention, I wish it to be fully understood that I do not confine myself to the precise steps set forth by way of explanation, as it is apparent that many changes and variations may be made therein, by those skilled in the art without departing

from the spirit of the invention, or exceeding the scope of the appended claims.

I claim:

1. A method of shearing fur pelts having a pelage composed of hair falling in different directions comprising shearing the pelage against one fall of the hair, and repeating the shearing operation consecutively against all the falls of the hair.
- 10 2. A method of shearing fur pelts having a pelage composed of hair falling in different directions from a center bald spot, comprising shearing the pelage against one fall of the hair through the center bald spot and repeating the shearing operation consecutively through the center bald spot against all the falls of the hair.
- 20 3. A method of shearing fur pelts having a pelage composed of hair falling in different directions from a center bald spot, comprising shearing the pelage against one fall of the hair through the center bald spot and over the other falls of hair and repeating the shearing operation consecutively through the center bald spot against and over all the falls of the hair.
- 25

4. A method of shearing calf skins comprising, shearing the pelage against one fall of the hair through the center bald spot and over the other falls, and repeating the shearing operation through the center bald spot consecutively five times against the other falls of the hair.

5. A method of shearing calf skins comprising, shearing the pelage against one fall of the hair in a line with the direction from the head to the tail of the pelt through the center bald spot, and over the fall of the hair and repeating the shearing operation consecutively five times at angles of 45 degrees to each preceding cut against and over the falls of the hair through the center bald spot.

6. A method of shearing fur pelts having a pelage composed of hair falling in different directions comprising shearing the pelage against one fall of the hair, and repeating the shearing operation consecutively against other falls of the hair.

In testimony whereof I affix my signature.

GEORGE J. LAEMMLE.
